Primary Examiner — Cynthia Ramirez*Assistant Examiner* — Laura H Yu(74) *Attorney, Agent, or Firm* — Cantor Colburn LLP**(57) CLAIM**

The ornamental design for a drum washing machine, as shown and described.

DESCRIPTION

FIG. 1 is a front perspective view of a drum washing machine, showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines illustrating portions of the drum washing machine form no part of the claimed design.

1 Claim, 7 Drawing Sheets(56)
